CABINET HOUSING FOR SIDE-LOADING TAPE PLAYER OR SIMILAR ARTICLE

Raymond J. Schmitz, Prospect Heights, and James F. Sellars, Jr., Addison, Ill., assignors to Motorola, Inc., Franklin Park, Ill.

Filed Feb. 11, 1971, Ser. No. 114,753

Term of patent 14 years

Int. Cl. D14—01
U.S. Cl. D26—14

Fig. 1

Fig. 2

Fig. 3

Fig. 4

Fig. 5

FIG. 1 a front perspective view of a cabinet housing for a side-loading tape player or similar article showing the front, top and left-hand side of our new design and having a pivoted cover in a partially open position to illustrate the reception of a tape player unit;

FIG. 2 is an end view of the left-hand side of the cabinet housing of FIG. 1;

FIG. 3 is a front view of the cabinet housing of FIG. 1 without the inclusion of the tape player unit;

FIG. 4 is a top plan view of the cabinet housing of FIG. 1 with the pivoted cover in its closed position;

FIG. 5 is a bottom plan view of the cabinet housing of FIG. 1; and

FIG. 6 is a rear view of the cabinet housing of FIG. 1. The broken lines are shown for illustrative purposes only.

We claim:

The ornamental design for a cabinet housing for a side-loading tape player or similar article, as shown and described.
